UNITED STATES PATENT OFFICE.

NORMAN B. HURD, OF NEW BRITAIN, AND WILLIAM C. ROWE, OF PLAINVILLE, CONNECTICUT, ASSIGNORS TO AMERICAN HARDWARE CORPORATION, OF NEW BRITAIN, CONNECTICUT, A CORPORATION OF CONNECTICUT.

HINGE.

1,180,153.

Specification of Letters Patent. Patented Apr. 18, 1916.

Application filed February 15, 1916. Serial No. 78,371.

To all whom it may concern:

Be it known that we, NORMAN B. HURD and WILLIAM C. ROWE, citizens of the United States of America, residing, respectively, at New Britain and Plainville, Connecticut, have invented a new and useful Hinge, of which the following is a specification.

Our present invention relates to hinges generally and special objects of the invention are to prevent rotation of the hinge pin or pintle and to lock the pintle against withdrawal when the door is in certain positions, as for instance, when the door is closed. In the accomplishment of these objects we employ in a preferred form of the invention, means in the shape of a washer non-rotatably held in a knuckle of one of the hinge leaves for preventing rotation of the pintle and means in the shape of a second washer carried by a knuckle on the other hinge leaf for preventing removal of the pin except in certain predetermined positions of the hinge leaves.

Other features and the details of construction will be understood from the following specification, attention being directed to the drawing forming a part thereof and wherein we have illustrated practical forms the invention may take.

In this drawing:—Figure 1, is a face view of a hinge constructed in accordance with and embodying the invention. Fig. 2, is a sectional view of the same taken substantially on the plane of the line 2—3 of Fig. 1 showing also the upper washer and indicating the hinge in the “door-closed” position with the hinge pin locked against withdrawal. Fig. 3, is a view on the same plane showing the hinge opened to a 90° position, wherein the hinge pin is released and can be freely removed. Fig. 4, is a perspective view of the several parts which constitute this form of the hinge. Fig. 5, is a similar view of a slightly different form of the hinge.

The two members or leaves of the hinge are designated 7 and 8, the member 7 in the illustration, being provided with a pair of hinge knuckles 9 and the member 8 with cooperating hinge knuckles 10, said knuckles having a bore 11 therethrough to receive the pintle 12. The pintle is secured against rotation by providing it with a flattened or

recessed portion 15 in one side thereof arranged to be engaged by an inwardly extending projection 16 on a washer 17 mounted in the case illustrated in an annular seat 18 surrounding the bore in the lowermost knuckle 10 of the hinge leaf 8. This washer is non-rotatably held in this seat by providing interengaging shoulders on the washer and knuckle, specifically illustrated as an outwardly projecting lug 19 on the washer engaged between the shoulders formed by cutting a notch in the edge of the annular seat, as indicated at 20 in Fig. 4. By locating this non-rotating washer in the lowermost knuckle, the hinge pin need be flattened only at the lower end portion thereof, specifically only on the portion which projects into the lower knuckle. The securing of the hinge pin against rotation in this way produces a “non-rising” pin.

The hinge pin is locked against withdrawal by means similar to the non-rotating means just described and consisting of a second washer 22 seated in an annular seat 23 surrounding the bore in the lower knuckle in the other hinge leaf and provided with an inwardly extending projection or lug 24 arranged to engage with transversely extending locking shoulders 25 on the pintle. This washer is held against rotation in its knuckle in a manner similar to the first washer by providing the interengaging shoulders 26 and 27 on the washer and knuckle respectively.

In the construction illustrated, the non-rotating washer and the locking washer are mounted in the meeting upper and lower faces of the knuckles on the two hinge leaves and the recess in the side of the pintle extends as far as the locking shoulders 25. It follows from this therefore that when the leaves are turned so as to bring the locking projection 24 on the upper washer and the non-rotating projection 16 on the lower washer into the same plane as indicated in Fig. 3, the hinge pin can be freely withdrawn and that when the hinge leaves occupy a position such as that indicated in Fig. 2 wherein the locking projection 24 overstands the locking shoulder 25 on the pintle, the pintle cannot be withdrawn.

The parts are usually so arranged that the pintle will be locked against removal when the door is closed as indicated in Fig.

2 but can be freely withdrawn when the door is fully opened in the position indicated in Fig. 3.

The form of the invention illustrated in Fig. 5 is similar to the first form illustrated except that in this case the non-rotating washer and the locking washer are of similar construction, the locking projection 24' on the locking washer 22' corresponding as 10 to shape to the non-rotating projection 16' on the non-rotating washer 17'. Also in this construction the interengaging shoulders which hold the washers against rotation are provided by forming the washers with 15 spurs or outstanding lugs 30 which take into the metal of the knuckles as indicated at 31 in Fig. 5 as the washers are forced into their seats. This construction has an advantage over the first in that the cost is reduced by 20 reason of the fact that both locking and non-rotating washers may be made from the same dies.

What we claim is:—

1. In a hinge construction, hinge leaves 25 having interengaging knuckles, a pintle engaged in said knuckles, a washer mounted in a knuckle of one of the hinge leaves, engaging shoulders on said knuckle and washer for securing said washer against 30 rotation, engaging means on said non-rotating washer and pintle for securing the pintle against rotation, a washer carried by a knuckle of the other hinge leaf, engaging shoulders on said knuckle and washer for 35 preventing rotation of said washer in respect to said knuckle and engaging means on said second washer and pintle for preventing removal of said pintle.

2. In a hinge construction, hinge leaves 40 having interengaging knuckles, a pintle engaged in said knuckles provided with a transversely extending locking shoulder and a recess in one side thereof, a washer non-

rotatably engaged in a knuckle of one of the hinge leaves and provided with a projection 45 engaging the recessed side portion of the pintle to thereby secure said pintle against rotation, a washer non-rotatably supported in a knuckle of the other hinge leaf and provided with an inwardly extending projection 50 engaging the locking shoulder on the pintle to prevent removal of the same.

3. In a hinge construction, hinge leaves having coöperating knuckles provided with a bore therethrough, washers seated in the 55 meeting upper and lower faces of two of the knuckles on the respective hinge leaves, projections on said washers extending inwardly into the bore and a pintle engaged in said bore having a recessed portion in one side 60 thereof receiving the projection on one of the washers and locking shoulders extending transversely from said recessed portion arranged to be engaged by the projection on the other washer.

4. In a hinge construction, hinge leaves having coöperating knuckles provided with a bore therethrough, the lowermost of said knuckles having a projection extending inwardly into the bore therein and the lower 70 knuckle of the opposite hinge leaf having a projection extending inwardly into the bore through the same, a pintle engaged in the bore through the knuckles having its lower end portion flattened at one side to pass by 75 the projection on the lower hinge knuckle whereby said pintle is held against turning by said lower knuckle and said pintle having transversely extending locking shoulders disposed in the plane of the projection on 80 the lower knuckle of the opposite hinge leaf to be thereby engaged by said projection and held against removal.

NORMAN B. HURD.
WILLIAM C. ROWE.
